SEWING MACHINE PRESSER FOOT

Patricia E. Russo, P.O. Box 543 (or 422 W. Santa Clara),
Santa Ana, Calif. 92702

Filed Jan. 27, 1975, Ser. No. 544,187

Term of patent 14 years

Int. Cl. D15—06

U.S. Cl. D70—2 B

FIG. 1

FIG. 5

FIG. 2

FIG. 3

FIG. 6

FIG. 4

FIG. 7

FIG. 1 is an isometric view of a sewing machine presser foot showing my new design;

FIG. 2 is a top plan view thereof;

FIG. 3 is a view in elevation of the left side thereof;

FIG. 4 is a bottom plan view thereof;

FIG. 5 is a view in front elevation thereof;

FIG. 6 is a view in elevation of the right side thereof;

and

FIG. 7 is a rear elevational view thereof.

I claim:

The ornamental design for a sewing machine presser foot, as shown.
